(57) CLAIM

The ornamental design for a beverage maker, as shown and described.

DESCRIPTION

FIG. 1 is a perspective view as seen from the top, front and right side of a beverage maker showing the new design;
FIG. 2 is a front view thereof;
FIG. 3 is a rear view thereof;
FIG. 4 is a right side view thereof (the left side view being the same);
FIG. 5 is a top view thereof; and,
FIG. 6 is a bottom view thereof.
The broken lines in the drawings are included for illustrative purposes only and form no part of the claimed design.
